ATTORNEY

UNITED STATES PATENT OFFICE.

WILLIAM MEYER, OF GLADBROOK, IOWA.

CEMENT CORNCRIB BLOCK.

Application filed October 4, 1921. Serial No. 505,299.

To all whom it may concern:

Be it known that I, WILLIAM MEYER, a citizen of the United States, residing at Gladbrook, in the county of Tama and State 5 of Iowa, have invented new and useful Improvements in Cement Cornerib Blocks, of which the following is a specification.

This invention relates to a building block formed of concrete and the like, the general 10 object of the invention being to provide the block with openings therein for ventilating the interior of the building and while the blocks are mainly designed for building corn cribs it will of course be understood that 15 the invention is not to be limited to this use.

Another object of the invention is to so form the openings that rain or snow water will drain therefrom to the exterior of the 20 building and the forms can easily be removed after the material from which the block is formed has set.

This invention also consists in certain other features of construction and in the combination and arrangement of the several 25 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a fragmentary view of a corn 35 crib constructed from my improved blocks.

Figure 2 is a face view of one of the blocks.

Figure 3 is a section on line 3—3 of Figure 2.

Figure 4 is an end view of the block.

Figure 5 is a top view.

Figure 6 is a face view of a corner block.

Figure 7 is an end view of a corner block.

Figure 8 is a face view of a half block.

45 In these views 1 indicates a main block, 2 a corner block and 3 a half block. These blocks are formed of any suitable material, such as concrete and the like, and each block is formed with a projecting panel 4 on its front face which is of less dimensions than the blocks. The corner block has a panel 4' on its end, this end being exposed when the block is placed in the row. Each block is also provided with a number of ventilating

50 openings 5 which pass transversely through the block. The openings are evenly distrib-

uted in the main block but only occur in one half of the corner block as the other half of this corner block will engage the end block of the row of the blocks at the abutting side of the building. The openings are also evenly distributed in the half block. These half blocks are used for completing the row where the row cannot be entirely composed of the main blocks. The openings 5 are each formed of an outer part 5' and an inner part 5'', the junction of the two parts being an appreciable distance from the center of the block so that the part 5' is of greater depth than the part 5''. The walls 70 of each part taper inwardly. The bottoms of both portions of each opening are of V-shape and they extend inwardly and upwardly to form a sloping valley, as shown at 5x, so that rain or snow water will drain 75 from the openings and due to the fact that the outer portion of each opening is of greater depth than the inner portion most of this water will drain to the exterior of the block and very little will find its way into 80 the interior of the building. I place screens 6 in the openings at the junction of the inner part with the outer part so as to prevent rodents or birds from entering the building. Such screens may be formed of 85 wire netting or a rod bent into U-shape and having its ends embedded in the block 1.

The ends of each block may be formed with a large vertically arranged groove 7 which will form an air space and small 90 grooves 8 at each side thereof for receiving the binding material. These grooves may also be formed in the top and bottom of the block.

It will thus be seen that a building constructed from my blocks will be thoroughly 95 ventilated and this is a very important feature in a building designed to hold corn and other grain. The building will be rat and mice proof, will not rot and is absolutely 100 fire proof. The corner blocks must be made right and left. The cribs can be made of rectangular shape with a center driveway and the openings are made small enough to prevent the ears of corn from 105 entering them.

It is thought from the foregoing description that the advantages and novel features of my invention will be readily apparent.

I desire it to be understood that I may 110 make changes in the construction and in the combination and arrangement of the

several parts, provided that such changes fall within the scope of the appended claims.

What I claim is:—

1. A building block of the class described having a ventilating opening passing transversely therethrough, the bottom of the opening sloping downwardly from a point adjacent the center to the ends and said bottom being of V-shape in cross section.

10 2. A ventilated building block of the character described having a panel on one of its sides and ends, a plurality of ventilating openings arranged transversely therethrough, said opening including an outer

part and an inner part with the junction of the two parts being an appreciable distance from the center of the block so that the outer part is of a greater depth than the inner part and the bottoms of each part being V-shaped in cross section and extending inwardly forming a sloping valley, a plurality of different size grooves formed on the ends, top and bottom of the blocks and means arranged in the ventilating openings at the junctions of the inner part with the outer part for the purpose specified.

In testimony whereof I affix my signature.

WILLIAM MEYER.
